(57) **ABSTRACT**

There is provided a method for driving an electrophoresis display device equipped with a plurality of pixel electrodes, each of the pixel electrode being provided for every pixel, a common electrode provided to oppose the plurality of pixel electrodes, and an electrophoresis element containing electrophoresis particles, the electrophoresis element being sandwiched by the plurality of pixel electrodes and the common electrode. The method includes driving the electrophoresis element and updating a display by a common voltage swing drive method in which a rectangular wave in which a first potential and a second potential are repeated is applied to the common electrode for not less than one cycle during a display update time in which the first potential or the second potential for moving the electrophoresis particles is applied to each of the pixel electrodes. A frequency of the rectangular wave is not less than 20 Hz.

BACKGROUND

1. Technical Field

The present invention relates to a method for driving an electrophoresis display device, an electrophoresis display device, and an electronic apparatus.

2. Related Art

A phenomenon (electrophoresis phenomenon) in which electrophoresis particles are moved by coulomb forces has been known, and an electrophoresis display device using the phenomenon has been developed.

The electrophoresis display device is equipped with a pixel electrode provided in each of a plurality of pixels, a common electrode provided to oppose the plurality of pixel electrodes, and an electrophoresis element that is sandwiched by the plurality of pixel electrodes and the common electrode and that contains electrophoresis particles. The electrophoresis display device performs a display drive by moving the electrophoresis particles by an electrical field occurred by a potential difference between the pixel electrodes and the common electrode.

For example, in JP-A-2002-149115, there is a description about “common voltage swing drive method” for performing update of display by switching the potential of each pixel electrode by using two types of potentials having a relationship of high and low and by also switching the potential of the common electrode by the two types of potentials.

Herein, the common voltage swing drive method will be described with reference to FIG. 16 and FIGS. 17A to 17C.

FIG. 16 is a diagram showing an example of a drive timing chart according to a conventional electrophoresis display device. FIGS. 17A to 17C are diagrams showing a behavior of black particles (electrophoresis particles) 1026 and white particles (electrophoresis particles) 1027 when driven in accordance with the timing chart of FIG. 16. Note that in FIGS. 17A to 17C, the black particles 1026 and the white particles 1027 are fully agitated and an image is to be displayed from a display state with gray.

In FIG. 16 and FIGS. 17A to 17C, a plurality of pixels 1040 are separated into a pixel 1040b for displaying black and a pixel 1040w for displaying white for description.

During a display update time t_x of FIG. 16, a high potential (first potential; H) is input to a pixel electrode 1035b of the pixel 1040b, and a low potential (second potential; L) is input to a pixel electrode 1035w of the pixel 1040w.

The display update time t_x is about 2 to 2.5 sec as is different depending on the property of the electrophoresis element. In FIG. 16, the display update time t_x is set to 2.0 sec.

A rectangular wave whose cycle is 200 to 500 ms is input to a common electrode 1037. In FIG. 16, a rectangular wave whose cycle is 40 ms (2.5 Hz) in which a high potential time of 200 ms and a low potential time of 200 ms are repeated is input during the display update time t_x . That is, during the display update time t_x , the rectangular wave is input for five cycles.

Note that the “common voltage swing drive method” in the invention refers to a driving method in which a rectangular wave in which the high potential time and low potential time are repeated is applied to the common electrode 1037 for at least not less than one cycle during the display update time t_x .

Next, a behavior of the black particles 1026 and the white particles 1027 when driven based on the timing chart of FIG. 16 will be described with reference to FIGS. 17A to 17C.

First, as shown in FIG. 17A, when the high potential (H) is input to the common electrode 1037, a potential difference occurs between the pixel electrode 1035w to which the low potential (L) is input and the common electrode 1037 in the pixel 1040w, and the white particles 1027 move to the side of the common electrode 1037 and the black particles move to the side of the pixel electrode 1035w.

On the other hand, in the pixel 1040b, no potential difference occurs between the pixel electrode 1035b to which the high potential (H) is input and the common electrode 1037. Accordingly, the black particles 1026 and the white particles 1027 do not move.

Next, as shown in FIG. 17B, when the low potential (L) is input to the common electrode 1037, no potential difference occurs between the pixel electrode 1035w to which the low potential (L) is input and the common electrode 1037, so that the black particles 1026 and the white particles 1027 do not move.

On the other hand, in the pixel 1040b, a potential difference occurs between the pixel electrode 1035b to which the high potential (H) is input and the common electrode 1037, and the black particles 1026 move to the side of the common electrode 1037 and the white particles move to the side of the pixel electrode 1035b.

The behavior when the first one cycle of the rectangular wave in FIG. 16 is applied to the common electrode 1037 is schematically shown in FIGS. 17A and 17B. The rectangular wave whose cycle is one rotation of the high potential (H) and the low potential (L) is further input to the common electrode 1037 for four cycles.

FIG. 17C shows a state right after the potential corresponding to five cycles containing the cycle of the aforementioned FIGS. 17A and 17B is applied. That is, FIG. 17C shows a state of each electrophoresis particles when the display update time t_x is finished. The white particles 1027 are gathered at the side of the common electrode 1037 of the pixel 1040w and white is displayed, and the black particles 1026 are gathered at the side of the common electrode 1037 of the pixel 1040b and black is displayed.

According to the common voltage swing drive method, the potential applied to the pixel electrode 1035 and the common electrode 1037 can be controlled by two values of the high potential (H) and the low potential (L). Accordingly, the voltage to be applied can be lowered a circuit structure can be simplified. Further, when a TFT (Thin Film Transistor) is used as a switching element of each pixel electrode 1035, there is a merit that the reliability of the TFT can be assured by a low voltage drive.

However, there is a problem described below in this method. There is a case that the potential input to the pixel electrode 1035 the common electrode 1037 is different from a predetermined voltage due to a current leak from a pixel circuit connected to the pixel electrode 1035, a resistance generated when an element substrate equipped with the pixel electrode and the common electrode provided to oppose the element substrate are electrically connected, a resistance owned by the common electrode 37, or the like.

Accordingly, a potential difference occurs in the pixel in which no potential difference should fundamentally occur and the electrophoresis particles may be flown back. As a result, there was a problem in that a phenomenon called flicker was generated. The electrophoresis particles are separated from the electrode and the contrast of a display image is temporally deteriorated by the flicker.

The flicker generated in the conventional common voltage swing drive method will be described with reference to FIG. 18. FIG. 18 is a graph showing reflectance measured in chronological order when the pixel 1040w is displayed with white.

In FIG. 18, the horizontal axis shows elapsed time, and driving based on the timing chart of FIG. 16 is performed during the display update time t_x that starts from the timing of about two sec, and thereafter, the display retention time t_y continues. Note that, the timing of about two sec when the display update time t_x is started shows a starting point of the measurement and the display retention time t_x shows a data retention time at the measurement, and there is no other intention in each thereof.

The longitudinal axis shows reflectance when the pixel 1040w is displayed with white and observed from the side of the common electrode 1037. Note that the reflectance does not reach 50% when the display update time t_x is passed. This is caused by display property of the electrophoresis element. The reflectance of the electrophoresis element to a standard white reflection plate is generally about 50% although different depending on the spec.

In FIG. 18, the area surrounded by the $\bigcirc$ of the graph at a lower portion shows a timing at which a first cycle of the rectangular wave is applied.

As shown in FIG. 17B, the low potential (L) is applied to the common electrode 1037 and the pixel electrode 1035w in pixel 1040w that displays white at the timing, so that no potential difference occurs and each electrophoresis particles are supposed to remain in the position. However, as shown in the $\bigcirc$ in the graph, the reflectance is lowered in reality. This is caused by a potential difference due to the aforementioned current leak or the like and shows that flicker is generated by flow back of the electrophoresis particles.

Further, the flicker generates not only in the first cycle, but also in the second cycle shown by the $\square$ although the level of flicker is reduced. Further, the flicker also generates a little in the third to fifth cycles.

The flickers of the levels can be recognized by a person. Accordingly, the user of the electrophoresis display device suffers from a visual stress due to the flicker.

SUMMARY

An advantage of some aspects of the invention is to provide a method for driving an electrophoresis display device superior in display quality, and to provide an electrophoresis display device and an electronic apparatus superior in display quality.

According to an aspect of the invention, there is provided a method for driving an electrophoresis display device equipped with a pixel electrode that is provided for a pixel, a common electrode provided to oppose the pixel electrode, and an electrophoresis element containing electrophoresis particles, the electrophoresis element being sandwiched by the pixel electrode and the common electrode. The method for driving an electrophoresis display device includes driving the electrophoresis element and updating a display by a common voltage swing drive method in which a rectangular wave in which a first potential and a second potential are repeated is applied to the common electrode for not less than one cycle during a display update time in which the first potential or the second potential for moving the electrophoresis particles is applied to the pixel electrode. A frequency of the rectangular wave is not less than 20 Hz.

Herewith, even when lowering of reflectance is occurred, the lowering occurs within a time that is too short to be recognized. Accordingly, a driving method of an electro-

phoresis display device that does not give a visual stress to the user and that is superior in display quality can be provided.

It is preferable that a period during applying the first potential and a period during applying the second potential in the rectangular wave are not less than 1 ms and not more than 25 ms.

Herewith, if the period during applying the first potential and the period during applying the second potential are not less than 1 ms, a momentum necessary for updating the display can be provided to the electrophoresis particles. Accordingly, responsiveness can be maintained. Further, if the period during applying the first potential and the period during applying the second potential are not more than 25 ms, lowering of reflectance is hardly recognized, so that display quality can be improved. Accordingly, a driving method of an electrophoresis display device having both responsiveness and display quality can be provided.

It is more preferable that a period during applying the first potential and a period during applying the second potential in the rectangular wave are not less than 5 ms and not more than 20 ms.

Herewith, if the period during applying the first potential and the period during applying the second potential are not less than 5 ms, a momentum necessary for updating the display can be provided to the electrophoresis particles. Accordingly, responsiveness can be improved. Further, if the period during applying the first potential and the period during applying the second potential are not more than 20 ms, lowering of reflectance becomes further difficult to be recognized, so that display quality can be further improved. Accordingly, a driving method of an electrophoresis display device in which both responsiveness and display quality are further improved can be provided.

According to another aspect of the invention, there is provided an electrophoresis display device including at least a pixel electrode that is provided for a pixel, a common electrode provided to oppose the pixel electrode, and an electrophoresis element containing electrophoresis particles, the electrophoresis element being sandwiched by the pixel electrode and the common electrode. Driving of the electrophoresis element for updating a display is performed by a common voltage swing drive method in which a rectangular wave in which a first potential and a second potential are repeated is applied to the common electrode for not less than one cycle during a display update time in which the first potential or the second potential for moving the electrophoresis particles is applied to the pixel electrode, and a control unit for controlling a frequency of the rectangular wave so as to be not less than 20 Hz is included.

Herewith, even when lowering of reflectance is occurred, the lowering occurs within a time that is too short to be recognized. Accordingly, an electrophoresis display device that does not give a visual stress to the user and that is superior in display quality can be provided.

It is preferable that the control unit controls a period during applying the first potential and a period during applying the second potential in the rectangular wave so as to be not less than 1 ms and not more than 25 ms.

Herewith, if the period during applying the first potential and the period during applying the second potential are not less than 1 ms, a momentum necessary for updating the display can be provided to the electrophoresis particles. Accordingly, responsiveness can be maintained. Further, if the period during applying the first potential and the period during applying the second potential are not more than 25 ms, lowering of reflectance is hardly recognized, so that display qual-

ity can be improved. Accordingly, an electrophoresis display device having both responsiveness and display quality can be provided.

It is more preferable that the control unit controls a period during applying the first potential and a period during applying the second potential in the rectangular wave so as to be not less than 5 ms and not more than 20 ms.

Herewith, if the period during applying the first potential and the period during applying the second potential are not less than 5 ms, a momentum necessary for updating the display can be provided to the electrophoresis particles. Accordingly, responsiveness can be improved. Further, if the period during applying the first potential and the period during applying the second potential are not more than 20 ms, lowering of reflectance is hardly recognized, so that display quality can be improved. Accordingly, an electrophoresis display device having both responsiveness and display quality can be provided.

It is preferable that the pixel is equipped with a pixel circuit, and the control unit employs an active matrix method for controlling the pixel via the pixel circuit.

Herewith, the driving can be separately performed for every pixel. Accordingly, an electrophoresis display device capable of displaying at a high resolution and with flexibility can be provided.

It is preferable that the pixel circuit is equipped with a storage device.

Herewith, the potential of the pixel electrode can be kept at a constant value during the display update time. Accordingly, an electrophoresis display device by which uniform contrast display can be obtained can be provided.

According to still another aspect of the invention, there is provided an electronic apparatus equipped with the electrophoresis display device according to the another aspect of the invention.

Herewith, even when lowering of reflectance is occurred, the lowering occurs within a time that is too short to be recognized. Accordingly, an electronic apparatus that does not give a visual stress to the user and that is superior in display quality can be provided.

BRIEF DESCRIPTION OF THE DRAWINGS

The invention will be described with reference to the accompanying drawings, wherein like numbers reference like elements.

FIG. 1 is a plan view schematically showing an electrophoresis display device.

FIG. 2 is a diagram showing a circuit configuration of a pixel.

FIG. 3 is a partial cross sectional view showing a display area.

FIG. 4 is a cross sectional view schematically showing a microcapsule.

FIG. 5 is a diagram showing a timing chart according to the electrophoresis display device.

FIGS. 6A to 6C are diagrams showing a behavior of electrophoresis particles.

FIG. 7 is a diagram showing a graph in which reflectance is measured in chronological order.

FIG. 8 is a plan view schematically showing an electrophoresis display device.

FIG. 9 is a diagram showing a cross sectional structure and an electrical structure of the electrophoresis display device.

FIG. 10 is a diagram showing a timing chart according to the electrophoresis display device.

FIG. 11 is a diagram showing a graph in which reflectance is measured in chronological order.

FIGS. 12A and 12B are each a diagram showing a timing chart according to a modification.

FIG. 13 is a front view showing a watch.

FIG. 14 is a perspective view showing an electronic paper.

FIG. 15 is a perspective view showing an electronic note.

FIG. 16 is a diagram showing an example of a timing chart of a conventional electrophoresis display device.

FIG. 18 is a diagram showing a graph in which reflectance is measured in chronological order.

DESCRIPTION OF EXEMPLARY EMBODIMENTS

Electrophoresis Display Device

Hereinafter, an electrophoresis display device of the invention will be described with reference to the accompanying drawings.

The embodiment shows an aspect of the invention and does not restrict the invention, and any modification can be made within the scope of the technical ideas of the invention. Further, in the drawings described below, the scale size, number, or the like of each element are different from those of the real element in order to provide clear visibility.

FIG. 1 is a plan view schematically showing an electrophoresis display device 5 of an active matrix driving method. The electrophoresis display device 5 is equipped with a display area 5B, a scanning line driving circuit (control unit) 61, a data line driving circuit (control unit) 62, and a controller (control unit) 63 around the area of the display area 5B. A plurality of scanning lines 61a is extended to the display area 5B from the scanning line driving circuit 61 and a plurality of data lines 62a is extended to the display area 5B from the data line driving circuit 62. The scanning line driving circuit 61 and the data line driving circuit 62 are electrically connected to the controller 63. Pixels 40 are arranged in a matrix manner along the extending direction (X axis direction) of the scanning line 61 and the extending direction (-Y axis direction) of the data line 62a.

FIG. 2 is a diagram showing a circuit configuration of the pixel 40. As shown in FIG. 2, the pixel 40 is equipped with a switching element (pixel circuit) 41, a latch circuit (storage device) 46, an electrophoresis element 32, a pixel electrode 35, and a common electrode 37. The scanning line 61a, the data line 62a, a low potential power source line 49, and a high potential power source line 50 are provided to surround the elements.

The switching element 41 is an n-channel transistor of a field effect type, and the scanning line 61a is electrically connected to a gate 41a and the data line 62a is electrically connected to a terminal 41b. The latch circuit 46 is provided between the switching element 41 and the pixel electrode 35. Power source of the latch circuit 46 is provided by the low potential power source line 49 and the high potential power source line 50. An input terminal N1 of the latch circuit 46 is connected to a terminal 41c of the switching element 41, and an output terminal N2 of the latch circuit 46 is connected to the pixel electrode 35.

Note that a low potential (L) is supplied to the low potential power source line 49 and a high voltage (H) is provided to the high potential power source line 50 when the control unit is in an operation state.

The latch circuit 46 is constituted by the combination of an inverter circuit formed by a p-channel transistor 43 and an

n-channel transistor **42**, and an inverter circuit formed by a p-channel transistor **45** and an n-channel transistor **44**.

In the latch circuit **46**, the p-channel transistor **45** and the n-channel transistor **44** are connected at the input terminal **N1**, and the p-channel transistor **43** and the n-channel transistor **42** are connected at the output terminal **N2**.

The gates of the p-channel transistor **45** and the n-channel transistor **44** are connected to the output terminal **N2** and the pixel electrode **35**, and the gates of the p-channel transistor **43** and the n-channel transistor **42** are connected to the input terminal **N1** and the switching element **41**.

The p-channel transistors **43, 45** are connected to the high potential power source line **50** and the n-channel transistors **42, 44** are connected to the low potential power source line **49**.

The latch circuit **46** having such a structure outputs the low potential from the output terminal **N2** when the input terminal **N1** is in the high potential and outputs the high potential from the output terminal **N2** when the input terminal **N1** is in the low potential. Further, the output potential of the latch circuit **46** is kept till the power source of the latch circuit **46** is turned off, so that a stable potential is input to the pixel electrode **35** connected to the output terminal **N2**.

FIG. 3 is a partial cross sectional view showing the display area **5B**. The electrophoresis display device **5** has a structure in which the electrophoresis element **32** is sandwiched between an element substrate **30** and a counter substrate **31**. The electrophoresis element **32** has a structure in which a plurality of microcapsules **20** is arranged in plan view.

A plurality of pixel electrode **35** are formed to correspond to the pixels **40** on the element substrate **30**. The element substrate **30** is made of a glass, plastic, or the like. As is omitted in FIG. 3, the scanning line **61a**, the data line **62a**, the switching element **41**, the latch circuit **46**, and the like shown in FIGS. 1, 2 are formed between the element substrate **30** and the pixel electrodes **35**.

The counter substrate **31** is positioned at the side at which an image is displayed in the electrophoresis display device **5** and is a transparent substrate made of a glass, plastic, or the like. The common electrode **37** is formed on approximately the entire surface of the counter substrate **31** at the side of the electrophoresis element **32**. The common electrode **37** is made of a transparent conductive material such as, for example, MgAg (magnesium silver), ITO (indium tin oxide), and IZO (indium zinc oxide).

FIG. 4 is a cross sectional view schematically showing a microcapsule **20**. The microcapsule **20** has a particle diameter of, for example, about 50 μm . The microcapsule **20** is a round body containing a disperse medium **21**, a plurality of black particles (electrophoresis particles), and a plurality of white particles (electrophoresis particles) **27**.

As for the material of the shell region of the microcapsule **20**, an acrylate resin such as poly methyl methacrylate, poly ethyl methacrylate, or the like, an urea resin, a polymer resin having translucency such as gelatine may be employed. The microcapsules **20** are sandwiched by the common electrode **37** and the pixel electrodes **35** as shown in FIG. 3, and one or a plurality of microcapsules **20** is disposed in one pixel **40**.

The disperse medium **21** is a liquid that disperses the black particles **26** and the white particles **27** in the microcapsule **20**. As for the material of the disperse medium **21**, for example, the one may be employed in which a surface active agent is blended in water, alcohol system solvent such as methanol, ethanol, isopropanol, butanol, octanol, methyl cellosolve, or the like, esters such as ethyl acetate, butyl acetate, or the like, ketones such as acetone, methyl ethyl ketone, methyl isobutyl ketone, or the like, aliphatic hydrocarbon such as pentane, hexane, octane, or the like, alicyclic hydrocarbon such as

cyclohexane, methylcyclohexane, or the like, aromatic hydrocarbon such as a kind of benzene having long-chain alkyl group such as benzene, toluene, xylene, hexylbenzene, hebutylbenzene, octyl benzene, nonyl benzene, decylbenzene, undecyl benzene, dodecylbenzene, tridecylbenzene, tetradecylbenzene, or the like, halogenated hydrocarbon such as methylene chloride, chloroform, carbon tetrachloride, 1,2-dichloroethane, or the like, carboxylic salt, various other oils, or the like or a blended material thereof.

The black particle **26** is a particle (polymer or an inorganic material) made of a black pigment such as, for example, aniline black, carbon black, or the like and for example, charged to positive polarity.

The white particle **27** is a particle (polymer or an inorganic material) made of a white pigment such as, for example, titanium dioxide, zinc flower, antimonous oxide, or the like, and for example, charged to negative polarity.

A charge control agent made of particles such as an electrolyte, a surface active agent, a metal soap, a resin, a gum, an oil, a varnish, a compound, or the like, a dispersant such as a titanium series coupling agent, an aluminum series coupling agent, a silane series coupling agent, or the like, a lubricant agent, a stabilizing agent, or the like can be added to the pigment constituting the particles as necessary.

Driving Method of the Electrophoresis Display Device

Next, a driving method of the electrophoresis display device **5** of the invention will be described.

FIG. 5 is a diagram showing a timing chart according to the 30 electrophoresis display device **5** of the invention. FIGS. 6A to 6c are diagram showing a behavior of the black particles (electrophoresis particles) **26** and the white particles (electrophoresis particles) **27**.

The plurality of pixels **40** are separated into the pixel **40b** for displaying black and pixel **40w** for displaying white for description in FIGS. 5, 6A to 6C.

A high potential (first potential; H) is input to the pixel electrode **35b** of the pixel **40b** and a low potential (second potential; L) is input to the pixel electrode **35w** of the pixel **40w** in a display update time **tx** of FIG. 5.

Further, a rectangular wave whose cycle is 40 ms in which a high potential time of 20 ms and a low potential time of 20 ms are repeated is input to the common electrode **37**. That is a rectangular wave whose frequency is 25 Hz (40 ms cycle) is input to the common electrode **37**.

Further in the embodiment, the display update time **tx** is set to 2.0 sec. Accordingly, a rectangular wave whose cycle is 40 ms is repeated for 50 cycles in the display update time **tx**.

Note that the display update time **tx** is not limited to 2.0 sec 50 and may be appropriately set between about 0.5 sec to 3.0 sec to match the spec. Further, in a display retention time **th** after the display update time **tx**, the low potential (L) is input to each of the pixel electrode **35b**, the pixel electrode **35w**, and the common electrode **37** and no potential difference occurs 55 between each pixel electrode **35b**, **35w** and the common electrode **37**, so that display is retained.

FIGS. 6A to 6C are diagrams showing a behavior of the black particles **26** and the white particles **27** at this time.

First, as shown in FIG. 6A, when the high potential (H) is 60 input to the common electrode **37**, a potential difference occurs between the pixel electrode **35w** to which the low potential (L) is input and the common electrode **37** in the pixel **40w**, and the white particles **27** move to the side of the common electrode **37** and the black particles **26** move to the side of the pixel electrode **35w**.

On the other hand, in the pixel **40b**, no potential difference occurs between the pixel electrode **35b** to which the high

potential (H) is input and the common electrode 37, so that the black particles 26 and the white particles 27 do not move.

Next, as shown in FIG. 6B, when the low potential (L) is input to the common electrode 37, no potential difference occurs between the pixel electrode 35w to which the low potential (L) is input and the common electrode 37, so that the black particles 26 and the white particles 27 do not move.

On the other hand, a potential difference occurs between the pixel electrode 35b to which the high potential (H) is input and the common electrode 37 and the black particles 26 move to the side of the common electrode 37 and the white particles 27 move to the side of the pixel electrode 35b.

FIG. 6A and FIG. 6B schematically show a behavior of the particles corresponding to the initial one cycle of the rectangular wave applied to the common electrode 37 in FIG. 5. 49 cycles of the rectangular wave whose cycle is constituted by the high potential (H) and the low potential (L) is further input to the common electrode 37.

FIG. 6C shows the state when 50 cycles of the potential containing the cycle of FIG. 6A and FIG. 6B is applied. That is, FIG. 6C shows a state of each electrophoresis particles at the time when the display update time t_x is finished. The white particles 27 are gathered at the side of the common electrode 37 of the pixel 40w and white is displayed, and the black particles 26 are gathered at the side of the common electrode 37 of the pixel 40b and black is displayed.

Next, FIG. 7 is a graph showing reflectance in chronological order when the pixel 40w is displayed with white. In FIG. 7, the horizontal axis shows elapsed time. Driving based on the timing chart of FIG. 5 is performed during the display update time t_x that starts from the timing of about 1.5 sec, and thereafter the display retention time t_h continues. Note that, the timing of about 1.5 sec when the display update time t_x is started shows a starting point of the measurement and the display retention time t_h shows a data retention time at the measurement, and there is no other intention in each thereof.

As shown in FIG. 7, when the reflectance is rapidly increased during the display update time t_x and thereafter transits to the display retention time t_h , the increase rate of the reflectance becomes moderate and the reflectance comes close to a fixed value.

In the embodiment, a rectangular wave whose frequency is 25 Hz (40 ms cycle) is input to the common electrode 37. Also in the electrophoresis display device 5 of the embodiment, during the low potential time in which no potential difference should occur, a potential difference occurs due to a current leak from a pixel circuit such as the latch circuit 46 connected to the pixel electrode 35, a resistance generated when the element substrate 30 supporting the pixel electrode 35 sandwiching the electrophoresis element 32 and the counter substrate 31 supporting the common electrode 37 are electrically connected, a resistance owned by the common electrode 37, or the like. This causes an adverse current of the electrophoresis particles. However, the frequency of the common electrode potential is higher than that in the conventional electrophoresis display device, so that the period when reflectance is lowered due to the adverse current is one-tenth of the conventional period, and the period is in a level that makes the user difficult to recognize the lowering.

Further, in the embodiment, the variation of the reflectance for every one cycle of the rectangular wave is smaller than that in the conventional one shown in FIG. 18. Specifically, the lowering of the reflectance observed in the conventional electrophoresis display device is about 3%. However, the lowering of the reflectance in the embodiment is not more than 0.5%. Also in this point, the lowering of the reflectance due to the adverse current is difficult to be recognized.

According to the electrophoresis display device 5 using such a driving method, effects described below can be obtained.

Display by the electrophoresis element 32 can be updated so that flicker does not stand by inputting a rectangular wave whose frequency is not less than 25 Hz (not more than 40 ms cycle) to the common electrode 37. Accordingly, a high quality display by which the user does not feel visual stress when updating display can be provided.

That is, by setting the high potential time and the low potential time respectively to 20 ms during the display update time t_x , a sufficient energy for moving each electrophoresis particle can be supplied and it becomes possible to prevent the flicker to stand.

Accordingly, a high quality display by which the user does not feel visual stress when updating display can be provided.

Further, in the above embodiment, the description is made when the frequency of the rectangular wave is 25 Hz (40 ms cycle). However according to results of experiments performed by the inventor, it has been confirmed that the similar effect can be obtained if the frequency of the rectangular wave is not less than 20 Hz (50 ms cycle). According to the results of the experiments, it is required that the frequency of the rectangular wave is within the range of 20 to 500 Hz (2 to 50 ms cycle). It is preferable that the frequency of the rectangular wave is within the range of 25 to 100 Hz (1 to 40 ms cycle).

Note that it is considered that the reason that the upper limit of the frequency is 500 Hz (2 ms cycle) is that an energy amount necessary for moving the black particles 26 and the white particles 27 can be supplied if each of the high potential time and the low potential time is not less than 1 ms.

By the driving conditions, a high quality display by which the user does not feel visual stress when updating display can be also provided similarly to the aforementioned embodiment.

Further, during the display retention time t_h in the aforementioned embodiment, the low potential (L) is input to each of the pixel electrode 35b, pixel electrode 35w, and the common electrode 37. However, this is not limited. For example, the pixel electrode 35b, the pixel electrode 35w, and the common electrode 37 are set to a high impedance state. The high impedance state denotes the state where there is no input from the control unit. Also in the state, since no potential difference occurs between each of the pixel electrodes 35b, 35w and the common electrode 37, display can be retained. Further, since the power source of the control unit can be turned off, the power consumption can be reduced.

Further, according to the embodiment, since the storage device is equipped in the pixel 40, the potential of the pixel electrode 35 can be kept at a constant value during the display update time t_x . Accordingly, a display having a uniform contrast can be obtained in which fluctuation of the potential of the pixel electrode 35 is restrained.

Application to Segment Driving Method

Note that the invention is also available when applied to a segment driving method. FIG. 8 is a plan view schematically showing an electrophoresis display device 105 of a segment driving method. The electrophoresis display device 105 is equipped with a display area 105B in which a plurality of segments (pixels) 140 are arranged, and a voltage control circuit 160. The voltage control circuit 160 and each segment 140 are electrically connected via a power source drive wire 161.

FIG. 9 is a diagram showing an electrical structure of the electrophoresis display device 105 with a cross sectional structure. The display area 105B is equipped with an element substrate 134 in which a plurality of segment electrodes (pixel

11

electrodes) 135 are provided for every segment 140, a counter substrate 136 equipped with a common electrode 137 commonly provided to all of the segment electrodes 135, and an electrophoresis element 132 formed by a plurality of micro-capsules 124 in which black particles 126 charged to positive polarity and the white particles 127 charged to negative polarity are enclosed.

The electrophoresis element 132 is sandwiched by the segment electrodes 135 and the common electrode 137.

Each segment electrode 135 is electrically connected to a voltage control circuit 160 via the power source drive wire 161 and a switch 165. The common electrode 137 is electrically connected to the voltage control circuit 160 via a common electrode drive wire 162 and the switch 165.

FIG. 10 is a diagram showing an example of a timing chart according to the electrophoresis display device 105 of the conventional segment driving method. Herein, the plurality of segments 140 are separated into the segment 140 for displaying black and the segment 140 for displaying white for description.

During the display update time t_x , a high voltage (H) is input to a segment electrode 137b of the segment 140 that displays black and a low potential (L) is input to a pixel electrode 137w of the segment 140 that displays white. Further, a rectangular wave whose cycle is 200 ms that repeats a high potential time of 100 ms and a low potential time of 100 ms is input to the common electrode 137. That is, a rectangular wave whose frequency is 5 Hz (200 ms cycle) is input to the common electrode 137.

Further, the display update time t_x is set to 1.0 sec in FIG. 10, so that the rectangular wave whose cycle is 200 ms is repeated for five cycles during the display update time t_x .

FIG. 11 is a diagram showing a graph in which the variation of the reflectance in the electrophoresis display device 105 of the conventional segment drive system is measured in chronological order.

In FIG. 11, the horizontal axis shows elapsed time and the high potential (H) is input to the segment electrode 135b and the low potential (L) is input to the segment electrode 135w during the display update time t_x that starts from the timing of about 0.4 second.

Further, a rectangular wave whose cycle is 200 ms (5 Hz) in which the high potential time of 100 ms and the low potential time of 100 ms are repeated is input to the common electrode 137. Thereafter, during the display retention time t_h , the low potential is input to each of the segment electrodes 135b, 135w, and the common electrode 137.

Further, the display update time t_x is set to 1 sec. That is, in the conventional driving method, a rectangular wave whose cycle is 200 ms is input for five cycles during the display update time t_x .

Note that the timing of about 0.4 sec when the display update time t_x is started shows a starting point of the measurement and the display retention time t_h shows a data retention time at the measurement, and there is no other intention in each thereof.

The area surrounded by the ○ in FIG. 11 shows a change of reflectance at the timing when the first cycle of the rectangular wave is applied.

As shown in FIG. 10, since the low potential (L) is applied to both of the common electrode 137 and the segment electrode 135w in the segment 140 that displays white at the timing, no potential difference occurs and each electrophoresis particle is supposed to remain in the position. However, as shown in the ○, the reflectance is lowered and a flicker is observed in reality.

12

Since then, also in the electrophoresis display device 105 of the segment driving method, as is omitted in the drawing, it is confirmed that the period in which lowering of the reflectance occurs can be reduced to not more than one-quarter similarly to FIG. 7 by applying a rectangular wave whose frequency is not less than 20 Hz (not more than 50 ms cycle) to the common electrode 137 for driving.

Note that in the segment driving system, it is also confirmed by experiences that the occurrence of the flicker can be reduced by the frequency of the rectangular wave similar to the embodiment. Accordingly, a high quality display in which flicker is reduced by which the user does not feel visual stress when updating display can be provided also in the segment driving method.

15 Modifications

FIGS. 12A, 12B are each a diagram showing a timing chart according to a modification. In the aforementioned embodiment, the rectangular wave having a constant frequency is sequentially applied to the common electrode 37 during the 20 display update time t_x . However, this is not limited thereto.

According to the occurrence mode of the flicker in FIG. 18, a flicker of a large size is observed in first and second cycles of the rectangular wave. Consequently, for example, a rectangular wave of 20 Hz may be applied during the first half of the 25 display update time t_x (25 cycles of the first half among the 50 cycles in FIG. 18) and a rectangular wave of 10 Hz may be applied during the 25 cycles of the second half to the common electrode 37 (FIG. 12A).

Further, during the display update time t_x , the frequency of 30 the rectangular wave may be reduced from 20 Hz, to 10 Hz, 5 Hz in a stepwise manner (FIG. 12B).

That is, the prevention effect of the flicker in the invention can be obtained as long as a rectangular wave whose cycle is not less than 20 Hz is applied at least during the first half of the 35 display update time t_x .

Electronic Apparatus

Herein, the case where the electrophoresis display device of the invention is applied to an electronic apparatus will be described. FIG. 13 is a front view of a watch 300. The watch 40 300 is equipped with a watch case 302, and a pair of bands 303 coupled to the watch case 302.

An electrophoresis display device (display panel) 305, a second hand 321, a minute hand 322, and an hour hand 323 are provided on the front surface of the watch case 302, and a 45 crown 310 and operation buttons 311 as operators are proved at the side surface of the watch case 302. The crown 310 is coupled to a core (omitted in the drawing) provided in the case and provided in an integrated manner (for example, two steps) with the core so as to be pushed and pulled in a multistep manner and so as to be freely rotated.

An image to be a background, a character string such as date, hour, or the like, a second hand, a minute hand, an hour hand, or the like can be displayed by the electrophoresis display device 305.

55 The watch 300 equipped with a display area in which flicker does not stand out and superior in display quality can be provided by equipping the electrophoresis display device of the invention.

FIG. 14 is a perspective view showing a structure of an 60 electronic paper 400. The electronic paper 400 is equipped with the electrophoresis display device of the invention as a display area 401. The electronic paper 400 has a flexibility and is constituted to be equipped with a main body 402 formed by a rewritable sheet having the same texture and 65 flexibility as the conventional paper.

Further, FIG. 15 is a perspective view showing a structure of an electronic note 500. The electronic note 500 is the one in

13

which a plurality of the electronic papers 400 shown in FIG. 14 are bundled and sandwiched by a cover 501. The cover 501 is equipped with display data input means not shown in FIG. 15 for inputting display data transmitted from, for example, an outer device. Herewith, change or update of a content to be displayed can be performed in accordance with the display data in the state where the electronic papers 400 are bundled.

The electronic paper 400 and the electronic note 500 in which flicker does not standout and equipped with a display area superior in display quality can be provided by equipping the electrophoresis display device of the invention.

The electrophoresis display device of the invention can be used in a display area of an electronic apparatus such as a cell-phone, a portable audio instrument, or the like besides the electronic paper 400 and the electronic note 500.

Herewith, an electronic apparatus in which flicker does not standout and equipped with a display area superior in display quality can be provided.

The entire disclosure of Japanese Patent Application No. 2007-226474, filed Aug. 31, 2007 is expressly incorporated by reference herein.

What is claimed is:

1. A method for driving an electrophoresis display device equipped with a pixel electrode that is provided for a pixel, a common electrode provided to oppose the pixel electrode, 25 and an electrophoresis element containing electrophoresis particles, the electrophoresis element being sandwiched by the pixel electrode and the common electrode, the method for driving an electrophoresis display device comprising:

driving the electrophoresis element and updating a display 30 by a common voltage swing drive method in which a rectangular wave in which a first potential and a second potential are repeated is applied to the common electrode for not less than one cycle during a display update time in which the first potential or the second potential for moving the electrophoresis particles is applied to the pixel electrode,

wherein:

the rectangular wave has a first frequency during a first portion of a display update time period such that the first potential and the second potential are alternately applied to the common electrode a plurality of times according to the first frequency during the first portion of the display update time period, the first frequency of the rectangular wave being not less than 20 Hz;

the rectangular wave has a second frequency during a second portion of the display update time period such that the first potential and the second potential are alternately applied to the common electrode a plurality of times according to the second frequency during the second portion of the display update time period, the second portion of the display update time period being later than the first portion of the display update time period.

2. The method for driving an electrophoresis display device according to claim 1, wherein

a period during applying the first potential and a period during applying the second potential in the rectangular wave are not less than 1 ms and not more than 25 ms.

3. The method for driving an electrophoresis display device according to claim 1, wherein

a period during applying the first potential and a period during applying the second potential in the rectangular wave are not less than 5 ms and not more than 20 ms.

4. The method for driving an electrophoresis display device according to claim 1, wherein the first frequency differs from the second frequency.

14

5. The method for driving an electrophoresis display device according to claim 1, wherein the second frequency is less than the first frequency.

6. An electrophoresis display device including at least a pixel electrode that is provided for a pixel, a common electrode provided to oppose the pixel electrode, and an electrophoresis element containing electrophoresis particles, the electrophoresis element being sandwiched by the pixel electrode and the common electrode, wherein

10 driving of the electrophoresis element for updating a display is performed by a common voltage swing drive method in which a rectangular wave in which a first potential and a second potential are repeated is applied to the common electrode for not less than one cycle during a display update time in which the first potential or the second potential for moving the electrophoresis particles is applied to the pixel electrode, and including a control unit for controlling a frequency of the rectangular wave,

wherein:

the rectangular wave has a first frequency during a first portion of a display update time period such that the first potential and the second potential are alternately applied to the common electrode a plurality of times according to the first frequency during the first portion of the display update time period, the first frequency of the rectangular wave being controlled so as to be not less than 20 Hz;

the rectangular wave has a second frequency during a second portion of the display update time period such that the first potential and the second potential are alternately applied to the common electrode a plurality of times according to the second frequency during the second portion of the display update time period, the second portion of the display update time period being later than the first portion of the display update time period.

7. The electrophoresis display device according to claim 6, wherein

the control unit controls a period during applying the first potential and a period during applying the second potential in the rectangular wave so as to be not less than 1 ms and not more than 25 ms.

8. The electrophoresis display device according to claim 6, wherein

the control unit controls a period during applying the first potential and a period during applying the second potential in the rectangular wave so as to be not less than 5 ms and not more than 20 ms.

9. The electrophoresis display device according to claim 6, wherein

the pixel is equipped with a pixel circuit, and the control unit employs an active matrix method for controlling the pixel via the pixel circuit.

10. The electrophoresis display device according to claim 9, wherein the pixel circuit is equipped with a storage device.

11. An electronic apparatus comprising the electrophoresis display device according to claim 6.

12. A controller for controlling an electrophoresis display device including at least a plurality of pixel electrodes, each of the pixel electrodes being provided for every pixel, a common electrode provided to oppose the plurality of pixel electrodes, and an electrophoresis element containing electrophoresis particles, the electrophoresis element being sandwiched by the plurality of pixel electrodes and the common electrode, the controller executing a method for driving the electrophoresis display device comprising:

15

driving the electrophoresis element and updating a display by a common voltage swing drive method in which a rectangular wave in which a first potential and a second potential are repeated is applied to the common electrode for not less than one cycle during a display update time in which the first potential or the second potential for moving the electrophoresis particles is applied to each of the pixel electrodes, 5

wherein:

the rectangular wave has a first frequency during a first portion of a display update time period such that the first potential and the second potential are alternately applied to the common electrode a plurality of times according to the first frequency during the first portion 10

16

of the display update time period, the first frequency of the rectangular wave being not less than 20 Hz; the rectangular wave has a second frequency during a second portion of the display update time period such that the first potential and the second potential are alternately applied to the common electrode a plurality of times according to the second frequency during the second portion of the display update time period, the second portion of the display update time period being later than the first portion of the display update time period.
